LINE-UP TABLE WITH MEANS FOR DRAWING
NON-Straight LINES

Charles O. Goss, Indianapolis, Ind., assignor to International Typographical Union of North America, Indianapolis, Ind.

Filed Sept. 16, 1958, Ser. No. 761,311

1 Claim. (Cl. 33—26)

This invention relates broadly to the printing art and, more particularly, relates to so-called "line-up" or "register" tables which are used in performing such make-up operations as lining, ruling, scoring negatives and the like.

In the co-pending application of Claire N. Brewer, Charles O. Goss and Harold L. Riddle, Serial No. 722,690, filed March 20, 1958, now Patent Number 2,957,244, granted Oct. 25, 1960 for Precision Ruling and Scribing Device for Line-up Tables, there is disclosed an improved straight-edge and lining device which may be applied to any line-up table for drawing straight lines on any paper, negative or the like which is placed on the work surface of the table. The present invention constitutes an improvement on the straight-edge and lining device disclosed and claimed in that co-pending application, and the principal object of this invention is to provide means which may be associated or combined with the straight-edge device of the co-pending application, or with any other suitably constructed straight-edge device, for producing a line other than a straight line such, for example, as a wavy line or a line of non-uniform thickness or darkness.

The invention is described in the following specification and is illustrated in the accompanying drawing, in which:

FIG. 1 is a perspective view of a part of a line-up table having associated with it a straight-edge device including the means provided by this invention;

FIG. 2 is an enlarged sectional view taken on line 2—2 of FIG. 1;

FIGS. 3 and 4 are enlarged, partial sectional views taken on lines 3—3 and 4—4, respectively, of FIG. 2, and

FIG. 5 illustrates three typical lines made by the use of the means provided by this invention.

This invention provides means for drawing one line or a plurality of spaced, wavy, broken, or other non-straight lines on a sheet of paper or a photographic negative or on any other sheet of material which is laid on the horizontal, usually glass surface 2 of a line-up table 4, although it will be understood that while the invention is described in this specification in connection with the lining of a sheet placed in a line-up table it is applicable to and operative with any structure having a flat upper surface on which a sheet may be laid. The line-up table 4 is preferably rectangular in shape having four sides, one of which is shown at 6 and against and along which a straight-edge device is adapted to be positioned and slidably moved. This ruling device comprises essentially a T-shaped structure 8 having an elongated straight-edge part 10 which extends across the upper surface 2 of the line-up table, and a cross-head 12 which is disposed outside of, and parallel to, and in engagement with the side edge 6 of the table. The elongated straight-edge part of the T-shaped structure is preferably constructed in the manner disclosed in the co-pending application referred to above and therefore is channel shaped in cross-section, having the horizontal bottom 14, front wall 16 and rear wall 18, the front wall 16 providing the straight-edge of the device.

Means are provided by the invention for operative association with the straight-edge part 10 of the T-square for movement along such part to inscribe a line on the

2

film negative, paper sheet or the like which is positioned on the table top 2. Such means are provided by a carriage which is indicated generally at 20 and which comprises a generally flat body part which in its operative position extends transversely of the straight-edge part 10 of the T-square and is provided on its lower surface with two pairs of wheels 22, 24 which, when the carriage is operatively positioned on the straight-edge part 10, rest on the upper surfaces of the walls 16, 18 of part 10, whereby the carriage occupies an inclined position on the part 10 of the T-square with its forward end 26 higher than its rear end 28. The forward end 26 of the carriage overhangs the higher front wall 16 and this overhanging part of the carriage is provided on its lower surface with a depending member 30 which has on its inner surface, which is adjacent and parallel and spaced outwardly from the wall 16, a pair of wheels 32 which are mounted in depending member 30 for rotation about vertical axes, only one of these wheels being shown in the drawings. These two wheels 32 are of such a size and are so positioned that when the carriage is in normal operative position on the walls 16, 18 of the straight-edge part 10, they engage the outer surface of the forward, higher wall 16 and therefore form a rolling contact between the carriage and that wall. A block 34, which is of substantial weight, is mounted on the lower, rear part 28 of the carriage and, because of this positioning, constantly exerts a force on the carriage tending to draw the wheels 32 into close rolling contact with the outer surface of wall 16, thereby maintaining a firm and positive engagement between the carriage and the straight-edge part 10. The forward, upper end of the carriage is provided with a bearing member 40 which extends laterally of the straight-edge part 10 and is substantially horizontal and is rigidly connected to the carriage. This bearing member has a shaft 42 journaled in it which extends outwardly of the front wall of the carriage and carries a disc 44 to the outer surface of which there is connected a supporting member 46 having a diametrical opening 48 therethrough within which a ruling pen or scribe 50 may be positioned. A tightening screw 52 is threaded into member 46 to provide means for adjusting and holding the ruling pen or scribe with respect to the carriage. A spring pressed detent 54 is carried by the disc 44 and cooperates with a member 56 which is mounted on the front face of the carriage to provide means for releasably holding the ruling pen or scribe in raised position.

Means are provided by this invention for causing the pen or scribe 50 to describe a wavy, broken or other non-straight line as the carriage 20 is moved along the straight-edge. Such means comprise an elongated template 60 which is mounted on the front or exterior surface of the front wall 16 of the straight-edge and which extends longitudinally thereof throughout the extent of movement of the carriage and is positioned between the exterior surface of the front wall 16 and the wheels 32 of the carriage. This template is provided with spaced openings 62 along its length or is otherwise given a desired external contour, so that as the carriage is moved along the straight-edge the wheels 32 of the carriage will follow the contour of the template and will therefore cause the carriage and the ruling pen carried by the carriage to be moved in the same way, thus producing a line corresponding to the contour of the template from end to end. It will be obvious that this contour may be made of any desired shape by pre-forming the template in any suitable or desired manner. Examples of lines which may be made by suitable pre-forming of the template are illustrated in FIG. 5 of the drawings but it will be understood that these lines are only typical of an almost infinite number which may be produced by the means provided by the invention.

While I have described and illustrated one form which my invention may take, it will be understood by those skilled in the art that other embodiments, as well as modifications of that disclosed, may be made and practiced without departing in any way from the spirit or scope of the invention, for the limits of which reference must be made to the appended claim.

What is claimed is:

A device for drawing a non-straight line or a plurality of such lines on a sheet positioned on the drawing surface of a line-up table, drawing board or the like having an edge, comprising a T-square having a cross-head part adapted to be positioned movably in engagement with said edge and a straight-edge part adapted to extend across said drawing surface, said straight-edge part comprising an elongated horizontal bottom part and front and rear walls extending along the side edges of the bottom part, the front wall being higher than the rear wall, an elongated generally flat template mounted in face-to-face relation on the flat outer surface of said front wall and extending substantially from end to end thereof, said template having cut-out parts extending longitudinally of the template to provide spaced segments along the surface of the template, said segments and cut-out parts forming with the outer surface of said front wall a non-straight contour of pre-determined shape, a carriage mounted on the front and rear walls of the

5
10
15

straight-edge part of the T-square for movement longitudinally thereof, marking means carried by such carriage having a part overhanging the front wall of the straight-edge part, at least one wheel rotatably mounted on said overhanging part and being in rolling contact with the outer surface of said front wall and the spaced segments of the template mounted thereon, and a weight mounted on the carriage at its lower end adjacent the rear wall of the straight-edge part and being operative to draw the overhanging part of the carriage and its wheel into firm engagement with the front wall of the straight-edge part and the template mounted thereon, whereby the carriage and the marking means carried thereby are given a movement corresponding to the contour of the template during movement of the carriage along the straight-edge part.
